UNITED STATES PATENT OFFICE.

CLEMENT C. CLAWSON, OF NEWARK, NEW JERSEY.

DESIGN FOR A CASE FOR COIN-RECEIVERS.

SPECIFICATION forming part of Design No. 25,280, dated March 24, 1896.

Application filed February 21, 1896. Serial No. 580,284. Term of patent 7 years.

To all whom it may concern:

Be it known that I, CLEMENT C. CLAWSON, a citizen of the United States, residing at Newark, in the county of Essex and State of New Jersey, have invented and produced a new and original Design for a Case for Coin-
5 Receivers; and I do hereby declare the following to be a full, clear, and exact description of the same, reference being had to the accompanying drawings, forming a part hereof.

The leading features of my new and original design for cases for coin-receivers are a rectangular base a , on which I have arranged 15 the four flat sides of the rectangular body A of the casing. The face or front a' of the casing is perfectly plain, while the side a^2 has in its lower left-hand corner a square opening a^3 . Directly in front of said opening a^3 is an 20 ornamental cup-shaped receiver b . The opposite side a^4 of the casing is also provided with a circular hole or opening a^5 near the bottom and to one side thereof, as clearly represented in Fig. 2. At the corners, formed 25 by the face a' and the two sides or end pieces a^2 and a^3 , are the upright corner-beads c and c' , of a peculiar ornamentation, being of a twisted or helical pattern or having a rope-like appearance. 30 The casing proper is topped off by the vertically-arranged sides d at the front and back, said sides being narrower at the top than at the bottom, and having their top and bottom edges parallel to form a geometrical figure 35 known as a "trapezoid." The two remaining sides d' are rectangular in outline and are connected with the upwardly-inclining edges

of said sides d and d' to form a perfect wedge-frustum, as will be clearly seen from an inspection of said Fig. 1. Said sides d at the front of the casing and the sides d' at the two ends of the wedge-frustum are provided with a series of parallel grooves d^2 , and connecting each two consecutive and parallel grooves d^2 are short vertical grooves d^3 , which alternate in position, substantially as illustrated, thereby giving said wedge-frustum the appearance of a roof covered with shingles. The top or smallest end of said wedge-frustum I have closed with a square or rectangular board or 50 cover e , having its edges e' suitably rounded, substantially as shown.

The essential feature of my new and original design for a case for coin-receivers, therefore, is the arrangement of a rectangular casing on a rectangular base, said casing having at its front edges corner-beads of a twisted or helical pattern, and a roof or covering on said rectangular casing, made like a wedge-frustum and ornamented with horizontal and vertical grooves, which are parallel, to produce a shingle-covered structure, substantially as shown.

Having thus described my invention, what I claim is—

The design for a case for coin-receivers, substantially as herein shown and described.

In testimony that I claim the invention set forth above I have hereunto set my hand this 19th day of February, 1896.

CLEMENT C. CLAWSON.
